(57) **CLAIM**

The ornamental design for a portable electrically-heated coffee mug, as shown and described.

DESCRIPTION

FIG. 1 is a perspective view of the portable electrically-heated coffee mug embodying the design of the present invention.

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 4 Drawing Sheets

FIG. 6.

FIG. 3.

FIG. 7.

FIG. 5.
